United States Patent Office.

LEVI HEYWOOD, OF GARDNER, MASSACHUSETTS, ASSIGNOR TO HEYWOOD,
BROTHERS & CO., OF SAME PLACE.

Design No. 2,858, dated January 14, 1868.

DESIGN FOR A CHAIR.

The Schedule referred to in these Letters Patent and making part of the same.

TO ALL WHOM IT MAY CONCERN:

Be it known that I, LEVI HEYWOOD, of Gardner, in the county of Worcester, and State of Massachusetts, have invented a new Design for a Chair, of which the following is a full, clear, and exact description, reference being had to the accompanying drawings making part of this specification, in which—

Figure 1 is a front elevation of a chair, representing my new design.

Figure 2 is a side elevation of the same.

My invention consists in a new design for the braces which hold the legs and seat of the chair together, as will now be described.

In the said drawings, A is the seat, and B B the legs of the chair. Between the legs, and secured thereto and to the seat A, are four braces, C, each of which is made in one piece, and bent around so as to form an arch, thus giving a neat and ornamental appearance to the chair. The bent piece D, which forms the back, encloses two scrolls, a; the back; however, may be of any other form, as my invention consists only in the design of the braces which hold the legs and seat of the chair together.

Claim.

What I claim as my invention, and desire to secure by Letters Patent, is—

The design for the braces C, which serve to hold the legs and seat of a chair together, substantially as shown and described.

Witnesses:

P. E. TESCHEMACHER,
N. W. STEARNS.

LEVI HEYWOOD.
